FIG.11

FIG. 1 is a top plan view of a section of a woven panel for ceilings, walls, and the like, showing my new design, it being understood that the design repeats both horizontally and vertically to complete the panel;

FIG. 2 is an end view of FIG. 1;

FIG. 3 is a side view of FIG. 1;

FIG. 4 is a top plan view of a section of a woven panel for ceilings, walls, and the like, showing an alternate design, it being understood that the design repeats both horizontally and vertically to complete the panel;

FIG. 5 is an end view of FIG. 4;

FIG. 6 is a side view of FIG. 4;

FIG. 7 is a top plan view of a section of a woven panel for ceilings, walls, and the like, showing another new design, it being understood that the design repeats both horizontally and vertically to complete the panel;

FIG. 8 is an end view of FIG. 7;

FIG. 9 is a side view of FIG. 7;

FIG. 10 is a top plan view of a section of a woven

panel for ceilings, walls, and the like, showing still another new design, it being understood that the design repeats both horizontally and vertically to complete the panel;

FIG. 11 is an end view of FIG. 10;

FIG. 12 is a side view of FIG. 10.

This is a continuation of my design applications Serial Numbers D. 64,296, D. 64,297, D. 64,298, and D. 64,299, all of which were filed on March 15, 1961, and now abandoned.

I claim:

The ornamental design for a woven panel for ceilings, walls, and the like, as shown.
